(57) **CLAIM**

The ornamental design for a step pad for vehicular side step, as shown and described.

DESCRIPTION

FIG. 1 is a top perspective view of the step pad for vehicular side step of the present invention showing my new design with the dotted lines depicting solely environmental structure and forming no part of the claimed design;

FIG. 2 is a top plan view thereof;

FIG. 3 is a side elevational view thereof;

FIG. 4 is a bottom plan view thereof; and,

FIG. 5 is an end view thereof.

The step pad is shown on an enlarged scale in FIGS. 2-5.
